UNITED STATES PATENT OFFICE.

JOSEPH ROBINSON, OF NEW YORK, N. Y.

AUTOMATIC TRAIN-PIPE CONNECTER.

Application filed September 17, 1921, Serial No. 501,233. Renewed March 5, 1929.

My invention relates to improvements in automatic train pipe connectors and has for its object to improve the interchange device used in such connectors and to improve 5 the supports for carrying the connectors. The invention resides in the combinations, arrangements and constructions hereinafter described, pointed out in the appended claims, and illustrated in the accompanying 10 drawings in which

Figure 1 is a side elevation of my improvement. In this view a part of the bracket and the resilient support is broken away.

Figure 2 is a sectional plan view of the coupling head and interchange device shown in Figure 1, and

Figure 3 is a rear view taken on the line 3—3 of Figure 1.

Referring now to the drawings:

My improvement comprises any suitable form of coupling head A having at its center an opening in which is rotatably mounted the enlarged forward end 4 of a hollow fitting or conduit 5 which threadingly receives at its rear end an interchange head 6 having approximately the contour of the standard air brake hand hose coupling, shown, for example, at 7 in the Forsyth Patent 740,749, 25 October 6, 1903. The interchange head 6 is located between the supporting mechanism hereinafter described and diverges laterally of the coupling head A immediately adjacent the rear side of the latter. At 7 the fitting 5 is provided with a hexagon portion to facilitate its assembly into the interchange head 6, and at 8 the interchange head is provided with a projection or finger 9 adapted to engage the rear side of the head to 30 limit the forward movement of the fitting 5 in the head and to position the interchange head 6 longitudinally with respect to the coupling head A. The aforesaid enlarged forward end of the fitting 5 forms a shoulder 35 against which a flange or projection 10 abuts, the flange being formed integral with the head or otherwise secured thereto and extending laterally of the opening in the head in which the fitting 5 is mounted.

On opposite sides of the interchange head 6 and preferably above and below the same, I extend through the coupling head A the prongs 11 of the member B, the prongs being riveted or otherwise secured to the head and 45 being formed integral with a pair of horizontally disposed straps 12 placed apart in

the horizontal plane as shown particularly in Figure 2. The straps 12 terminate at their rear ends in a vertically extending flange 13 which normally abuts the rear 60 face of a suitable bracket C, the lower end of the bracket being extended downwardly through the opening between the straps 12 and having mounted in that portion thereof which lies between these straps a suitable tie rod 14, the tie rod having universal movement in the supporting bracket C and being formed as illustrated and described in my co-pending application Serial No. 364, 401, for improvements in automatic train 70 pipe connectors filed March 9th, 1920. A suitable supporting spring D is anchored to the bracket C by the aforesaid tie rod 14 and serves to maintain the coupling head A at the limit of its forward movement. For a 75 fuller description and illustration of the tie rod 14, the bracket C and the spring D reference is made to the above mentioned co-pending application. The novel features of these elements not being claimed in the 80 present application they are not detailedly illustrated in the accompanying drawings.

At opposite sides the bracket C is provided with a trunnion 15 which extends laterally through an elongated lock or opening 16 formed in the straps 12 of the member B, the straps being adapted to slide upon the trunnions or projections 15. By this arrangement the member B is supported on the bracket C and undue rotation of the 90 coupling head A about its longitudinal axis is prevented.

In Figure 2 the usual train pipe hose 17 is shown provided at its lower end with the ordinary and well known standard hand operated hose coupling 18, the latter being shown connected into the interchange head 6 of my improvement which operation is accomplished by rotating the interchange head 6 upwardly in the coupling head A to 100 bring it into coupling position with the coupling 18 whereupon it is rotated downwardly into the interlocked position with the coupling as shown in Figure 2. When it is desired to effect connection between a car 105 having my improvement and one not provided therewith, the hose 17 is disconnected from the interchange head 6 by rotating the latter upwardly and is then connected across in front of the coupling head A into the train 110 pipe hose of the unequipped car. The reverse of this operation will assemble the

coupling 18 into the interchange coupling 6.

No claim is herein made to the novel means for supporting the coupling head A herein illustrated and described, the right 5 being reserved to claim such novel features in a subsequent application divisional of this application. It will be noted that a suitable form of gasket is mounted in the enlarged end 4 of the fitting 5 and is adapted to make 10 a butt joint with a complementary gasket in an opposing coupling head. The gasket is indicated at 19.

What I claim is:

1. An automatic train pipe connector having in combination, a coupling head, a support therefor, a train pipe hose having thereon a coupling adapted to be connected to the hose of a car not equipped with an automatic connector, and means to detachably connect 15 the train pipe hose to said head, said means including a fitting rotatably mounted in the head, a laterally diverging interchange head connected to the fitting between said support and said coupling head, the interchange head 20 being rotatable with the fitting, said coupling in said train pipe hose being arranged to be connected into said interchange head by rotating the latter and said fitting.

2. An automatic train pipe connector having in combination, a coupling head, a support therefor, a train pipe hose, and means to detachably connect the train pipe hose to said head, said means including a fitting rotatably mounted in the head and fixed 30 against longitudinal movement therein, a laterally diverging interchange head connected to the fitting between said support and said coupling head, the interchange head 35 being rotatable with the fitting, and a coupling in said train pipe hose arranged to be connected into said interchange head by rotating the latter and said fitting.

3. An automatic train pipe connector having in combination, a perforated coupling head, a hollow fitting rotatably mounted in said perforation and having a shoulder, a laterally extending projection engaging said shoulder to limit the movement rearwardly 45 of said fitting in said perforation, a support for said head, a train pipe hose having at one end a coupling, and means to detachably connect said coupling to said fitting, said means comprising an interchange head having substantially the 50 contour of a standard air brake hand hose coupling, the interchange head being connected to said fitting and rotatable therewith and diverging laterally of said coupling head immediately adjacent the rear side of the latter.

ally of said coupling head immediately adjacent the rear side of the latter.

4. An automatic train pipe connector having in combination, a coupling head provided with an opening, a flange extending into said opening, a hollow fitting having an enlarged forward end rotatably occupying said opening and directly abutting said flange, an interchange head diverging laterally of said coupling head and threadingly connected to said fitting and rotatable therewith, a support for said coupling head positioned at the rear of said interchange head 60 and including a member which spans the interchange head and is connected to said coupling head on opposite sides of the interchange head, and a train pipe hose having at one end a coupling adapted to be connected 65 into said interchange head upon rotation of the latter and said fitting.

5. An automatic train pipe connector having in combination, a coupling head provided with an opening, an abutment extending into the path of said opening, a fluid conduit having an enlarged forward end rotatably occupying said opening and bearing directly upon said abutment, an interchange head diverging laterally of said coupling 70 head and threadingly connected to said fitting and rotatable therewith, said interchange head being provided with a projection adapted to engage said coupling head to limit the forward movement of said fitting 75 in said opening, a support for said coupling head positioned at the rear of said interchange head, and a train pipe hose having a coupling adapted to be connected into said interchange head by rotating the latter and 80 said fitting.

6. An automatic train pipe connector having in combination, a perforated coupling head, a hollow fitting rotatably mounted in said perforation, a support for said head, a train pipe hose having at one end a coupling, and means to detachably connect said coupling to said fitting, said means comprising an interchange head having substantially the 90 contour of a standard air brake hand hose 95 coupling, the interchange head being connected to said fitting and rotatable therewith and diverging laterally of said coupling head immediately adjacent the rear side of the latter.

In testimony whereof I hereunto affix my signature.

JOSEPH ROBINSON.
